P. Gallaher
ATTORNEY.

UNITED STATES PATENT OFFICE.

FREDERICK W. SANBORN, JR., OF DENVER, COLORADO, ASSIGNOR TO ALLISON MOTORS, INC., OF DENVER, COLORADO, A CORPORATION OF COLORADO.

VALVE-GUIDE-ALIGNING TOOL.

Application filed May 8, 1925. Serial No. 28,864.

It is often found that the valve guide openings in internal combustion engine blocks are out of alignment, that is, they are not perpendicular to the face of the 5 block or to the axis of the cam shaft. This invention relates to a device for reborning and truing these valve guide openings.

In a device of this character, it is essential that the boring tool be perfectly centered over the valve seat in the engine block 10 so that when the reboring operation has been completed the valve will rotate in perfect contact with its seat. It is also essential that the axis of the valve guide opening 15 be perpendicular with the face of the engine block and with the axis of the cam shaft. If the former be not true, the valve will not seat. If the latter be not true there will be a side thrust upon the valve shafts which 20 will result in rapid wear upon the valve shaft and guide.

To provide a reboring tool which will automatically center itself in the valve seat is the principal object of this invention.

Another object of this invention is to provide a device that will ream the valve 25 stem guide openings in engine blocks absolutely perpendicular to the face of the block and to the axis of the cam shaft without adjustment.

Still another object is to so construct a device of this character that it may be readily attached to the present engine blocks without the necessity of clamps or drilling 35 and tapping additional openings.

A still further object is to so arrange the reaming device that it may be operated from one of the usual portable drilling machines.

Other objects and advantages reside in 40 the detail construction of the invention, which result in simplicity, economy, and efficiency, and which will become more apparent from the following description.

In the following detailed description of 45 the invention, reference is had to the accompanying drawing which forms a part hereof. Like numerals refer to like parts in all views of the drawing and throughout the description.

50 In the drawing:

Fig. 1 is a side elevation of the invention in use upon an engine block. The engine block in this view is shown in vertical section.

Fig. 2 is a plan view of an engine block 55 illustrating the invention applied thereto.

Fig. 3 is a bottom view, looking upward, of my improved tool.

Fig. 4 is a vertical cross section through the invention and a portion of the engine 60 block.

Those parts of the usual engine block which are illustrated on the drawing will be designated as follows: Engine block 10, cylinders 11, valve seats 12, cylinder head studs 65 13, valve 14, valve guide 15, valve guide opening 16, valve spring 17, valve lifter 18, and cam shaft 19.

The invention comprises a vertical sleeve 20 carrying supporting flanges 21, bifurcated as shown at 31. The lower face of the flanges is planed perfectly perpendicular to the axis of the sleeve 20. In the upper extremity of the vertical sleeve 20 a bearing 22 is secured. Through which, passes a rotatable and longitudinally moveable boring shaft 23, provided at its lower extremity with a cutting blade 24.

A centering cone 25, formed on the lower extremity of a sliding bearing 26, projects 80 at the bottom of the sleeve 20 and acts as a lower bearing for the boring shaft 23. A recess 27 is formed in the bottom of the sleeve 20 for the reception of the cone 25. A helical spring 28 is arranged to surround the shaft 23 and be compressed between the bearings 22 and 26. The cutting blade 24 is secured in place by means of a set screw 29 and is of a length equal to the desired finished diameter of the valve guide opening 16.

The bifurcations in the flanges 21 are for the reception of the cylinder studs 13 found in the usual engine block. These cylinder studs are arranged in staggered relation as illustrated in Fig. 2 so that the invention may be placed over a valve seat 12 at an angle thereby engaging two of the studs 13 in the bifurcations in the flanges 21. The angle of placement of the device is alternated as it is moved from 100 valve seat to valve seat, as illustrated in broken line at 30, Fig. 2. The bifurcations 31 have sufficient length and breadth to allow the device to be moved in any direction upon the engine block, after being placed on the 105 studs.

In the usual device of this character, the boring shaft must be centered by hand over

the valve seat. In the present device the perpendicular to the axis of the cam shaft. centering requires no skill or thought on As the flanges are drawn down to the face the part of the operator since the centering of the block the centering cone 25 will recede 35 cone 25 will center the device automatically. The spring 28 allows the centering cone to move upward or downward to accommodate itself to various depths and diameters of valve seats.

When the device has been secured in place 10 as above described, a portable drill such as illustrated at 34 is attached to the upper extremity 35 of the boring shaft 23 so as to actuate it and cause the cutting blade 24 to ream out the valve guide opening 16. After 15 the opening has been reamed to a larger diameter, a length of tubing 35 is placed around the regular valve guide 15 so that it may be forced into place as before.

In setting up the device, the cone 25 is placed in a valve seat 12. Since the cone is concentric with the boring shaft the latter will now be automatically centered with relation to the valve seat. Nuts 32 are placed on the studs and the flanges 21 drawn down 25 against the face of the block 10. Since the boring shaft 23 is perpendicular to the lower face of the flanges it will be automatically brought to a perpendicular position relative to the face of the block 10, and, since, from 30 the method of its manufacture, the face of the block 10 is parallel to the axis of the cam shaft 19, the boring shaft 23 will be also

35 into the sleeve compressing the spring 28. While a specific form of the improvement has been described and illustrated herein, it is desired to be understood that the same 40 may be varied, within the scope of the appended claim, without departing from the spirit of the invention.

Having thus described the invention, what I claim and desire secured by Letters Patent is:—

45 A boring tool comprising a cylinder; a flange carried by said cylinder at the lower end and at right angles to the axis thereof and having slotted openings for securing said flange to the work; a bearing secured in 50 said flange to the work; a bearing secured in the upper end of said cylinder; a second bearing slidably mounted in the lower extremity of said cylinder; and an enlarged 55 conical head carried by said second bearing and arranged to project into a counter-bore at the lower end of said cylinder; a shaft 60 slidably and rotatably passing through both of said bearings and a spring arranged to be compressed between said bearings, said cylinder acting as a guide for said conical head.

In testimony whereof, I affix my signature.

FREDERICK W. SANBORN, JR.
